SEWING MACHINE

Yoshiaki Eguchi, Tokyo, Japan, assignor to Janome
Sewing Machine Co., Ltd., Tokyo, Japan

Filed Apr. 26, 1967, Ser. No. 6,845

Term of patent 14 years

(Cl. D70—1)

FIG. 1

FIG. 2

FIG. 3

FIG. 4

FIG. 1 is a side elevational view of a sewing machine showing my new design;

FIG. 2 is a top plan view thereof;

FIG. 3 is an elevational view of one end face, and
FIG. 4 is an elevational view of the other end face.

The essential features of the design reside in the portions shown in full lines on the drawing.

I claim:

The ornamental design for a sewing machine, as shown and described.
